CHANNING WHITMAN, OF BUFFALO, NEW YORK, ASSIGNOR TO FLEXLUME CORPORATION, OF TONAWANDA, NEW YORK, A CORPORATION OF NEW YORK

PROTECTIVE SHIELD FOR INCANDESCENT LAMPS

Application filed July 17, 1929. Serial No. 378,908.

This invention relates to a protective cap or shield for incandescent lamps such as are employed in the illumination of signs characterized by a hollow casing having translucent display portions in its walls.

A substantial item of the cost of maintaining such signs is the expense of the replacement of broken lamps. This breakage is for the most part due to the dripping or spattering of cold water upon the highly heated surfaces of the lamp bulbs, it being understood that in driving rain storms or showers or in the thawing of accumulated snow the water passes in some degree into the casing through the numerous interstices incident to its construction.

Modern practice requires for the illumination of signs of the kind described nitrogen or other suitable gas filled electric lamps. In any arrangement of such lamps between a horizontal and an upright position there is at the uppermost part of the bulb a small area which becomes highly heated, much more so than the rest of the area of the bulb. It is this excessively heated portion of the lamp bulb which is particularly exposed to spattering or dripping rain water or snow and which becomes cracked as a result, the remainder of the bulb not being heated to such an extent as to be seriously liable to cracking by contact with cold water.

The object of the invention is to overcome the above disadvantages by means of a shield or cap applicable to lamps of various diameters and which may be readily adjusted upon the lamp to a fit, preferably a substantially conforming fit, over and close to the uppermost exposed surface thereof, regardless of the angle at which the lamp may be mounted, and which by virtue of its form and arrangement relatively to the lamp does not substantially impair the illuminating efficiency of the lamp.

The invention is illustrated in the accompanying drawings in which:—

Figure 1 is a top plan view of the shield applied to a horizontally positioned lamp.

Figure 2 is a side elevation of the same.

Figure 3 is a side elevation of the shield applied to a vertically positioned lamp.

Figure 4 is a partial sectional view of the shield showing the manner of securing the gripping fingers thereto.

The lamp protector, as illustrated, consists of a disc 5 of suitable material, e. g. metal 55 preferably having a concave surface and adapted to lie close to and cover a portion of the surface of the lamp bulb 6. The cap 5 is applicable to lamps of the various sizes employed in electric signs of the kind described, the sizes usually ranging from forty to one hundred watts. Said cap is of a size sufficient to cover the portion of the bulb which becomes excessively heated during the illumination of the lamp, the diameter of the cap being in any case substantially less than the diameter of the major portion of the lamp bulb. The cap 5 is provided with resilient gripping fingers 7 which engage the lamp and permit universal adjustment of the cap 60 to position the same upon the upper side of the lamp irrespective of the angle at which it is mounted. The gripping fingers are preferably formed from wires suitably secured to the cap. As illustrated, these fingers 7 65 constitute the ends of two wires crossed upon the top of the cap 5, the wires being secured to the cap by the passing of the ends thereof through the apertures 8 about the marginal portion of the cap and bending them sharply 70 outwardly against the under side of the cap to conform to the shape of the bulb. This method of forming and attaching the gripping fingers to the cap insures a permanent connection between the two as well as permitting the positioning of the cap closely 75 against the lamp. The adjustable character of the protector permits its use upon lamps positioned either horizontally or vertically within the sign casing. 80

Having fully described my invention, I claim:—

1. A shield adapted to protect an incandescent lamp consisting of a disc having a degree of concavity such that it may be fitted substantially conformably upon said lamp so as to overlie a part of the area thereof subtended by a chord of less extent than the diameter of the lamp, two pairs of apertures formed in said shield and a resilient wire 85 90 95 98

passing through each of said pairs of apertures and adapted to conformably engage said lamp to permit adjustment of the shield about the lamp to cover a portion of the upper exposed surface thereof regardless of the angle at which the lamp is mounted, said wires crossing at a point over said cap.

2. A shield adapted to protect an incandescent lamp consisting of a disc having a degree of concavity such that it may be fitted substantially conformably upon said lamp so as to overlie a part of the area thereof subtended by a chord of less extent than the diameter of the lamp, two pairs of apertures formed in said shield and a pair of resilient crossed U-shaped wires, the end of which pass through said apertures to conformably engage said lamp to permit adjustment of the shield about the lamp to cover a portion of the upper exposed surface thereof regardless of the angle at which the lamp is mounted.

In testimony whereof I affix my signature.
CHANNING WHITMAN.
